UNITED STATES PATENT OFFICE.

MICHAEL A. LYNCH AND HARRY WILSON, OF WASHINGTON, DISTRICT OF COLUMBIA.

FUSE FOR EXPLOSIVE PROJECTILES.

SPECIFICATION forming part of Letters Patent No. 678,367, dated July 16, 1901.

Application filed August 16, 1900. Serial No. 27,105. (No model.)

To all whom it may concern:

Be it known that we, MICHAEL A. LYNCH and HARRY WILSON, citizens of the United States, residing at Washington, in the District of Columbia, have invented new and useful Improvements in Fuses for Explosive Projectiles, of which the following is a specification.

Our invention relates to improvements in percussion-fuses for the bases or points of explosive projectiles; and it has for one of its objects to provide a fuse embodying a primer, a firing-hammer, and a guard, which latter is normally interposed between the primer and the hammer, so as to protect the former from the latter, and is calculated when the projectile is fired from a gun to be moved by its inertia and the axial rotation of the projectile to uncover and expose the primer to the action of the hammer. A guard such as defined permits of the projectile being handled and transported with safety, and this notwithstanding but a very light shearing-pin may be employed to normally hold the hammer away from the primer with a view of insuring the release of the hammer when the projectile is fired, for it will be seen that in case the projectile is dropped or accidentally strikes against an object with sufficient force to shear the pin the guard over the primer or percussion-cap will effectually prevent the hammer from striking the primer and exploding the projectile. While this is so, it will be appreciated that the guard is subject to sure movement by its inertia and the centrifugal action of the projectile incident to the firing thereof, and hence does not detract from the reliability—that is, the exploding qualities—of the projectile in action.

Another object of the invention is to provide in a fuse a firing-hammer which operates by virtue of its inertia at the time of fire to disconnect itself from the fuse-stock and one which, while effectually held against casual rotary and rectilinear movement or creeping in the stock subsequent to its disconnection therefrom and incident to the flight of an explosive projectile, so as to avoid premature explosion thereof, may be depended upon to ignite the primer when the projectile is arrested either by striking an object head on

or in a slanting manner. By virtue of the firing-hammer being securely held against casual movement or creeping with respect to the fuse-stock subsequent to its disconnection therefrom, as stated, it will be observed that in the event of the projectile being dropped or struck against an object with sufficient force to release the hammer from the stock said hammer will remain in the position it assumes after being thus released. From this it follows that the hammer contributes very materially to the safety with which the projectile may be handled and transported and that it renders the projectile perfectly safe, even when the guard over the primer is omitted from the fuse.

Another object is to provide in a fuse a firing-hammer which depends for reliability in action both upon its weight and the tension of a spring which it embodies, and either, for if one should bind or otherwise fail the other will impel the firing-plunger of the hammer against the primer with sufficient force to ignite the latter.

Other advantageous features of the invention will be fully understood from the following description and claims when taken in conjunction with the annexed drawings, in which—

Figure 1 is a longitudinal diametrical section illustrating a base-fuse embodying our invention, the parts of said fuse being shown in the positions they occupy before the projectile to which the fuse is applied is fired. Fig. 2 is a similar view illustrating the movable parts in the positions they assume when the projectile is fired. Fig. 3 is a similar view illustrative of the positions the movable parts assume when the projectile strikes an object either head on or in a slanting manner. Fig. 4 is a detail transverse section taken in the plane indicated by the broken line 4 4 of Fig. 1 looking in the direction indicated by arrow. Fig. 5 is a detail perspective view of the guard. Fig. 6 is a similar view of the firing-plunger of the hammer. Fig. 7 is a perspective view of the body or casing of the hammer. Fig. 8 is a similar view of one of the sear-pins. Fig. 9 is a detail section illustrating our improved fuse as embodying the well-known gas shearing sys

tem of releasing the hammer. Figs. 10 and 11 are other modifications.

Referring by letter to the said drawings, and more particularly to Figs. 1 to 8 thereof, A is the casing or stock of our improved fuse, which in the preferred embodiment of the invention is provided with exterior screw-threads *a* and an end flange *b* for engagement with the body of a projectile in the usual manner. Interiorly the casing or stock is provided with a bore *c*, a diametrically-enlarged or counter bore *d*, an ignition-chamber *d'*, and a sealing-plate *d''* at the end of the same. It is also provided interiorly with a primer-holder or partition *e*, which has a recess *f* in its rear side to receive a primer or percussion cap *B* of any suitable construction, and also has a passage *g* leading from the recess *f* to the forward side of the holder for permitting the flame to gain access to the explosive in the chamber *d'* when the primer is ignited.

C is the hammer of the fuse, and *D* is the guard for normally protecting the primer against the action of the hammer. The guard is normally interposed between the hammer and primer and rests in engagement with the holder *e*, and is calculated when the projectile carrying the fuse is fired to be thrown back out of engagement with the partition by its inertia and then moved to one side by the centrifugal action incident to the rotation of the projectile to uncover and expose the primer to the action of the hammer.

In the preferred embodiment of the invention the guard *D* comprises a head *h*, adapted to rest against the rear side of the holder *e* and rabbeted or otherwise provided with a projection *i* of a size to enter the recess *f*, and a shank *j*, which is pivotally connected by a pin *k* or other suitable means to the holder *e* after the manner illustrated. The guard as a whole, or at least the shank thereof, is formed of metal or other material susceptible of being readily bent, and hence it follows that when the projectile carrying the fuse is fired the inertia of the guard will throw the head of the same back and out of engagement with the recess *f* in holder *e* and in so doing will bend the shank of the guard rearwardly, leaving said guard free to swing out of alignment with the primer or from between the same and the hammer, so as to expose the primer to the action of the hammer and insure the explosion of the projectile when the same strikes an object. It also follows that the guard will remain in a position between the hammer and primer until the shell is rotated by the rifling in the gun from which it is fired, and therefore there is no liability of the guard being moved out of alignment with the primer when the shell is handled or transported and no danger of the primer being ignited and the projectile exploded even if said projectile is forcibly dropped or struck against an object.

Notwithstanding the fact that the guard,

as above pointed out, contributes very materially to the safety of handling and transporting the projectile it will be seen that it is sure to be thrown out of the way by its inertia and the centrifugal action of the projectile when the same is fired, and therefore does not detract in any way from the reliability or exploding quality of the projectile in action, which is an important desideratum.

The hammer *C* in the preferred embodiment of the invention comprises a body or casing, which is of a diameter to snugly fit the bore *c* of stock *A* and is provided in its forward end with a recess *m* and adjacent to its forward end with radially-disposed apertures *n*, which communicate with said recess, a hollow firing-plunger *p*, which is arranged in the recess *m* and is provided with a point *q* and a circumferential groove *r* of angular form in cross-section, and sear-pins *s*, which rest in the apertures *n* of plunger *p* and also in the groove *r* of plunger *p*, their inner ends being beveled in conformity to the groove, as shown. The hammer *C* also comprises a coiled spring *t*, which is arranged in the hollow firing-plunger *p* and interposed between the same and the rear wall of the body or casing, as shown. The hammer as a whole is normally held in the position shown in Fig. 1 by a transverse shearing-pin *E*, which extends transversely through the stock *A* and the body or casing of the hammer and may, because of the protection afforded by the guard *D* and the safety qualities of the hammer, be very light and weak. This in order to insure the release of the hammer from the stock when the projectile is fired.

In the practice of our invention the several movable parts of the fuse normally rest in the positions shown in Fig. 1. At the moment the projectile is fired the hammer *C* is thrown backwardly by its inertia and the pin *E* is sheared by the shearing-plunger *l* after the manner shown in Fig. 2. The inertia of the guard *D* operates to throw the same backwardly and out of engagement with the recess *f* in partition *e*. Incident to the axial motion imparted to the projectile by the lands of the rifling in the gun from which it is fired the guard *D* will be thrown to one side by the centrifugal action, so as to expose the primer *B* to the action of the hammer *C*. During the flight of the projectile the guard *D* will have assumed a position such as shown in Fig. 3; but the hammer *C* will be effectually held in the position shown in Fig. 2 and against casual rotary or rectilinear movement or creeping. This is due to the fact that the pressure exerted by the strong spring *t* against the firing-plunger *p* tends to forcibly move said plunger forwardly, and by virtue of the coacting beveled portion or groove *r* of the plunger and the complementary inner ends of the sear-pins *s* operates to press said sear-pins radially outward and with considerable power against the wall of the bore *c*, with the result that great friction is created between

the pins and the wall of the bore *c*, and the hammer is securely held against casual movement in the stock, as stated. The holding of the hammer *C* against casual movement subsequent to its disconnection from the stock is highly advantageous, since it precludes premature explosion of a projectile during the flight thereof. It is also advantageous because it effectually prevents ignition of the primer in the event of the projectile being dropped or accidentally struck against an object with sufficient force to shear the pin *E*, and hence contributes materially to the safety with which the projectile may be handled and transported. When the projectile strikes an object either at right angles or in a slanting manner, the arrest of the projectile will cause the hammer to forcibly move forward. Incident to such forward movement of the hammer and as soon as the sear-pins *s* pass out of the bore *c* and into the counterbore *d* the tension of the spring *t*, acting against and pressing the firing-plunger *p* forwardly, will force said sear-pins outwardly, with the result that the firing-plunger *p* will be released from the shearing-plunger *l* and forcibly impelled by the spring *t* against the primer. The spring *t* is thus enabled to impel the plunger *p* forwardly, for it will be seen that the radial outward movement of the sear-pins serves, in addition to releasing the firing-plunger *p* from the body or casing *l*, to hold said body or casing against retrograde movement.

It will be appreciated from the foregoing that when the projectile is arrested both the weight of the hammer as a whole and the spring *t* will tend to forcibly impel the point *q* of the plunger *p* against the primer, and it will also be appreciated that if the spring binds or otherwise fails to act the weight of the hammer as a whole will be sufficient to ignite the primer, while if the body or casing binds after it has moved sufficiently far to carry the sear-pins out of the bore *c* and into the counterbore *d* the spring *t* will impel the plunger *p* forwardly with sufficient force to ignite the primer.

We prefer to have at least the shank of the guard *D* of metal that is susceptible of being readily bent; but it is obvious that the said shank might be of resilient material and that other expedients might be resorted to in order to accomplish the purposes for which the guard is designed. We also desire it understood that while we prefer the specific construction and relative arrangement of parts embraced in this the preferred embodiment of our invention we do not desire to be understood as confining ourselves to such specific construction and arrangement of parts, as such changes and modifications may be made in the practice of the invention as fairly fall within the scope of our claims. We further desire it understood that while shown as a base-fuse our improved fuse, with modifications which are obvious and need not be

mentioned, is susceptible of being used to advantage as a point-fuse.

The construction shown in Fig. 9 is similar to that shown in Figs. 1 to 4, with the exception that the shearing-pin is joined to and extends rearwardly from the body of the hammer, so as to be severed by the well-known gas shearing system, which is unnecessary to describe herein.

When desirable, the circumferential groove of the firing-plunger may be of circular form in cross-section, in which event sear devices in the form of balls will be employed in lieu of the pins *s*, as shown in Fig. 10 of the drawings.

In the construction shown in Fig. 11 the forward end of the firing-plunger *p* is made conical in order to perform the function ascribed to the groove *r* in Figs. 1 to 3 and also to operate after the manner of a cam to push the guard *D* to one side in the event of the centrifugal action of the projectile failing to move the guard laterally sufficiently far to enable the firing-plunger to strike the primer. It will be seen that after the guard *D* is thrown by its inertia back and out of engagement with the primer-holder, if the centrifugal action of the projectile moves the guard laterally but a short distance the conical forward end of the firing-plunger, engaging the edge of the guard, will throw the guard laterally to one side, and hence the firing-plunger will be free to strike the primer.

Having described our invention, what we claim, and desire to secure by Letters Patent, is—

1. In a fuse for explosive projectiles, a stock, a primer, a hammer in the stock, and means for normally holding the hammer against movement in the stock; said hammer having spring-actuated means engaging the stock and adapted to permit the hammer to be driven rearwardly in the stock by its inertia when the gun is fired and the hammer is released from the means for holding it against movement in the stock, and also adapted to hold the hammer against casual movement toward the primer, subsequent to its said rearward movement.

2. In a fuse for explosive projectiles, a primer, a holder therefor, having a recess, and a bendable primer-guard pivotally connected to the primer-holder so as to adapt it to swing laterally, and having a portion normally engaging the recess of the primer-holder and adapted to be disengaged therefrom by the bending of the guard when the projectile is fired from a gun.

3. In a fuse for explosive projectiles, a primer, a holder therefor having a recess, means for igniting the primer, and a bendable primer-guard pivotally connected to the primer-holder whereby it is adapted to swing laterally, and having a portion normally engaging the recess of the primer-holder and adapted to be disengaged therefrom by the

bending of the guard when the projectile is fired from a gun.

4. In a fuse for explosive projectiles, a stock, a primer, a hammer arranged in the stock and having a firing-plunger and a spring tending to move said plunger toward the primer, and means co-operating with said plunger and the stock for holding the hammer against creeping in the stock.

10 5. In a fuse for explosive projectiles, the combination of a stock, a primer, and an igniting-hammer for the primer arranged and adapted to move in the stock, and comprising a body, a spring-backed firing-plunger carried thereby, and means operated by the pressure of the spring against the firing-plunger whereby said firing-plunger is normally held against movement with respect to the body.

20 6. In a fuse for explosive projectiles, a stock, a primer-igniting hammer arranged in the stock, and comprising a body, a spring-backed firing-plunger carried thereby, and means co-operating with the firing-plunger and stock for holding the body against creeping in the stock, and the firing-plunger against casual movement with respect to the body.

25 7. In a fuse for explosive projectiles, a stock, having a bore, and a hammer arranged in the stock and having a spring-backed firing-plunger, and means operated by said firing-plunger and normally engaging the walls of the bore in the stock for normally holding the firing-plunger against movement with respect to the body, and for normally holding the hammer as a whole against casual movement with respect to the stock.

30 8. In a fuse for explosive projectiles, a stock, a hammer therein comprising a body, and a spring-actuated firing-plunger carried thereby, and means operated by the firing-plunger and engaging the stock for normally holding the firing-plunger against movement with respect to the body, and means for permitting the release of the firing-plunger from the body incident to movement of the hammer.

45 9. In a fuse for explosive projectiles, a stock, a hammer comprising a body and a spring-actuated firing-plunger carried thereby, and means on the hammer engaging the stock, whereby the firing-plunger is held against movement with respect to the body, and the hammer is held against creeping forward in the stock, and means in the stock whereby the firing-plunger is released from the body incident to movement of the hammer, substantially as specified.

50 10. In a fuse for explosive projectiles, a stock, a hammer comprising a body and a spring-actuated firing-plunger carried thereby, means detachably connecting the hammer to the stock, and means on the hammer in engagement with the stock for normally holding the hammer against casual creeping forward in the stock, and the firing-plunger against movement with respect to the body

55 and means in the stock whereby the firing-plunger is released from the body incident to movement of the hammer.

11. In a fuse for explosive projectiles, a stock, a hammer comprising a body or casing and a spring-actuated firing-plunger carried thereby, a shearing-pin engaging the body or casing and the stock, and means on the hammer co-operating with the stock for normally holding the hammer against casual creeping forward, and the firing-plunger against movement with respect to the body or casing and means for automatically effecting the release of said firing-plunger, substantially as specified.

60 12. In a fuse for explosive projectiles, a stock having a bore and a counterbore, an igniter-hammer comprising a body corresponding in diameter to the bore of the stock and having a recess in one end and radial apertures communicating with said recess, a spring-backed firing-plunger arranged in the recess of the body, and having a beveled portion, and sear devices arranged in the apertures of the body, and normally engaging the walls of the bore in the stock, and having inner beveled ends normally held in engagement with the beveled portion of the firing-plunger by the said walls of the bore of the stock.

65 13. In a fuse for explosive projectiles, a stock having a bore, and a play-space for a sear device in advance of the same, an igniter-hammer comprising a body arranged in the bore of the stock, a spring-actuated firing-plunger carried by the body and having a bevel, and a sear device carried by the body and normally engaging the walls of the bore and having a bevel normally engaging that of the firing-plunger whereby the hammer is held against creeping, and casual release of the plunger from the body is prevented.

70 14. In a fuse for explosive projectiles, the combination of a stock having a play-space for a sear device, and an igniting-hammer comprising a body, a spring-pressed firing-plunger carried thereby, and a sear device carried by the body, and interposed between and normally engaging the firing-plunger and the stock, to hold the hammer against creeping and the firing-plunger against casual release.

75 15. In a fuse for explosive projectiles, the combination of a stock having a play-space for a sear device, a wall therein having a recess in one side, a primer arranged in said recess, a bendable primer-guard pivotally connected to the wall and having a portion normally resting in the recess thereof, an igniter-hammer comprising a body, and a spring-pressed firing-plunger carried thereby, means for normally holding the hammer against creeping in the stock, and means operated by the firing-plunger and engaging

the stock for holding the hammer against creeping and the plunger against casual release from the body, substantially as specified.

16. In a fuse for explosive projectiles, a stock having a bore and a play-space for a sear-pin in advance of the same, a hammer comprising a body arranged in the bore of the stock, a spring-actuated firing-plunger carried by the body and having a circumferential groove of angular form in cross-section, and a sear-pin carried by the body and normally engaging the walls of the bore in the stock and having a conical portion normally seated in the groove of the firing-plunger, substantially as specified.

17. In a fuse for explosive projectiles, a stock having a bore and a play-space for a sear-pin in advance of the same, a hammer comprising a body arranged in the bore of the stock, a spring-actuated firing-plunger carried by the body and having a conical forward end, and a sear-pin carried by the body and normally engaging the walls of the bore in

the stock and having a surface conforming to and normally engaging the conical end of the firing-plunger.

18. In a fuse for explosive projectiles, a stock having a bore and a counterbore in advance of the same, a primer-igniting hammer comprising a body arranged in the bore of the stock, a spring-pressed firing-plunger carried by the body, a sear device carried by the body and normally engaging the wall of the bore in the stock, and coacting means on the firing-plunger and the sear-device whereby the latter is pressed against the wall of the bore by the spring behind the firing-plunger.

In testimony whereof we have hereunto set our hands in presence of two subscribing witnesses.
